UNITED STATES PATENT OFFICE.

EDWARD HANAK AND GEORGE HOEPNER, OF SAN FRANCISCO, CALIFORNIA,
ASSIGNORS TO THE UNION SCALE AND MANUFACTURING COMPANY, OF
SACRAMENTO, CALIFORNIA.

AUTOMATIC WEIGHING-SCALE.

SPECIFICATION forming part of Letters Patent No. 660,794, dated October 30, 1900.

Application filed November 13, 1899. Serial No. 736,769. (No model.)

To all whom it may concern:

Be it known that we, EDWARD HANAK and GEORGE HOEPNER, citizens of the United States, residing in the city and county of San Francisco, State of California, have invented 5 an Improvement in Automatic Weighing-Scales; and we hereby declare the following to be a full, clear, and exact description of the same.

10 Our invention relates to automatic weighing-scales and improvements therein; and it consists in a novel arrangement of an oscillating tilting compartment weighing-bucket with relation to a fixed discharge, so that the 15 compartments are alternately filled and discharged, latches for holding the bucket in either position to which it may be tilted, means for disengaging after the bucket is filled, and a novel arrangement of feed or supply hopper.

20 It also comprises details of construction which will be more fully explained by reference to the accompanying drawings, in which—

Figure 1 is a sectional elevation of the apparatus. Fig. 2 is a transverse section showing a bucket of modified form. Fig. 3 is a side elevation of a modified form of bucket. Fig. 4 is a detail of a latch mechanism. Fig. 5 is a transverse section of the feed-hopper, 30 and Fig. 6 is a perspective view of the same. Fig. 7 is a view from the side of the machine opposite to that shown in Figs. 5 and 6 and showing the automatic cut-off mechanism.

As shown in the present drawings, A is a 35 scale-beam fulcrumed at B, and C is a compartment weighing-bucket centrally supported upon the scale-beam, as shown at D.

As we have illustrated our invention, two 40 different forms of bucket are shown having the same general principle of operation, neither of which has any movable valve, gate, or shutter, and both are so poised with relation to the fulcrum about which they tilt that they are turned by the weight of the load in 45 one compartment to place that compartment in position to discharge and the other one simultaneously in position to be filled from the source of supply.

In Fig. 1 the diverging bottoms are always 50 inclined downward and outward and alter-

nately close against fixed abutments, while, as shown in Fig. 2, these bottoms are alternately tilted downwardly to discharge and upwardly when the compartment is to be filled.

The bucket has a vertical partition through 55 its center dividing it into two compartments, and it is adapted to tilt about the pivot-point D, so that the upper ends of these compartments are alternately brought into line with the feed or supply hopper E and so that material from this hopper will fall into one compartment until a sufficient amount has been received therein to cause the scale-beam to turn about its fulcrum and sink when the 60 latching devices to be hereinafter described are disengaged, so that the weight of the bucket will tilt it into position to discharge, at the same time presenting the other compartment of the bucket to receive material 65 from the source of supply. The opposite compartments of the weighing-bucket diverge from the central partition in each direction, as shown at c, and form the two discharges for the compartments.

As illustrated in Fig. 1, the lower part of 70 the bucket oscillates below the point of suspension and between two hangers F, fixed to and dependent from the scale-beam and carrying at the lower ends fixed shutters or abutments G. These abutments are so placed 75 that when the bucket tilts in one direction, so as to present the empty compartment to the source of supply, the discharge-mouth upon that side will be in contact with the stationary abutment G, and will thus be closed. At the same time the tilting of the bucket 80 will have withdrawn the discharge-mouth upon the opposite side from its stationary closure G, and it will thus be opened, so as 85 to allow the material to flow out from this compartment, while the other is being filled. This enables us to dispense with movable gates, shutters, or valves of any description.

In order to hold the bucket at either angle 90 when tilted, we have shown latches H, fulcrumed, as shown at I, and having vertical shoulders or catches h. It is intended to operate these latches either by gravitation, by 95 spring, or other pressure, and without fur- 100

ther mention of any particular means we desire it to be understood in all future mention of these latches that they will be so operated.

5 *J* are rollers or stops fixed upon the side of the tilting bucket and so disposed that when the bucket has been tilted to its farthest limit in one direction one of the latches *H* will drop, so that its shoulder *h* falls behind the roller or stop *J*, and thus holds the bucket in this 10 position until it has been filled sufficiently to cause it to counterbalance the scale-beam and sink. As it thus sinks with relation to the latch-levers, these latter being fulcrumed to the stationary outer case *K* and having 15 their movable ends resting upon supports, the downward movement of the loaded bucket will carry the stops *J* below the latch *h*, when the weight of the material in the bucket will immediately tilt it to the opposite side. The 20 latches *h* have their lower edges curved or inclined, so as to move easily over the stops *J*, and when one has been disengaged, so that the bucket tilts in that direction, the other will move over its stop *J* until the lat- 25 ter has passed the end of the latch *h*, when the latch will drop and lock the bucket in that position, this being possible because as soon as the bucket commences to discharge it becomes enough lighter than the weight on 30 the scale-beam to allow the latter to again tilt and raise the bucket, so that it will be in position to again engage the latch and catch.

In order to insure the disengagement of the latch when the bucket has been filled, we 35 have shown in Fig. 4 a supplemental lever *O*, fulcrumed at *O'* and connected by a rod *P* with a lever *Q*, so fulcrumed that one end is in position to be struck by the bucket when the latter sinks after being filled. This con- 40 tact is made by a contact point or device at *R*, which is so adjusted as to strike the end of the lever *Q* when the bucket is loaded and descends by counterbalancing the scale-beam. The lever *Q* then acts through the rod *P* to 45 tilt the lever *O*, the point of which strikes the projecting end of the latch-lever *H* and insures the disengagement of the catch *h* from the stop *J*.

In Figs. 2 and 3 we have shown a modification of the weighing-bucket, which in this 50 case is in the form of a semicylinder having a central partition dividing it into two quadrant-shaped compartments. These compartments are fulcrumed, so as to tilt, as in the first-described bucket, about the pivot-point *D*. As shown in Fig. 2, the bucket is tilted so that one of the compartments stands beneath the supply device and in the form of a *V*-shaped hopper, while the other one at right 55 angles therewith is so tilted that the material can discharge over its lower edge and pass down through the conducting-passage in the outer casing. When the compartment has been tilted around its support *D* until the 60 first-named one is in position to discharge upon the opposite side of the center, the one which has just discharged will be returned to

an upright position beneath the source of supply. The latch mechanism *H*, *h*, and *j* operates in essentially the same manner as previously described. In this case the tilting compartment-bucket *C* is supported upon the end of the scale-beam *A*, which extends axially with relation to the bucket, as shown in Fig. 3. In order to insure the tilting of the 75 bucket constructed in this manner, the center of support *D* is at a short distance above the bottom *c* of the compartment, so that whenever either of the compartments is in 80 position and has received its load there will be a sufficient overbalancing to that side of the central line to insure the tilting of the bucket as soon as released.

The supply or feed hopper *E* is constructed with convergent directing boards or wings *S* 85 near the top, and rods extending in line with this converging support the direction-boards *T* at essentially right angles with the boards *S* and interior thereto, so that material falling upon the boards *S* will be directed against the boards *T*, the current again broken by these boards throwing the material outwardly against the inner sides of the hopper and eventually allowing it to fall through into the 90 weighing-bucket.

In supplying some kinds of material it may be found desirable to have the directing-boards *T* separated, so that a portion of the material will fall between them, in addition to that which has its direction changed by the 100 boards *S* and *T*. In other cases it is desirable to close the boards *T* together, which is done by sliding the wings *S* downwardly upon the swinging sides *E'* until they meet at the apex, as shown in dotted lines, Fig. 5, and then 105 all the material can be directed outwardly against the sides of the hopper. When separated from each other, diverging direction-boards *U* are fixed in line beneath the space between the boards *T*, so that material which 110 falls through this open space will strike upon these direction-boards *U* and be diverted against the sides of the hopper, thus breaking up the current of the material and preventing it falling with such an impact as will 115 tend to choke or clog the delivery-passage.

Between the source of supply and the weighing-bucket is a notched gate 10, which is connected with one arm of a fulcrumed lever 11. The other arm is connected by a rod 12 with a hinged tilting discharge-chute 13, so disposed that the material leaving the weighing-bucket is directed to flow through this chute. The outer end of the chute has an arm 14 and an adjustable weight 15, which 120 serves to counterbalance the discharge-chute and normally hold its receiving end up beneath the discharge-opening through which the material passes from the weighing-bucket. The angle of the chute 13 is such that the material flowing through it normally will not 125 alter its position; but if the chute should become clogged or overloaded the increased weight would overcome that of the counter- 130

balance 15 and cause the chute to tilt about its pivot-point, and acting through the connection 12 and lever 11 it will temporarily close the gate 10 until the discharge-chute is relieved of the surplus weight and returns to its normal position. We have here described this regulating device as applied to weighing apparatus; but we do not limit it to such use, since it will be manifest that this automatic regulation of passing material is equally important under all conditions in which a regular flow and discharge are desirable.

Having thus described our invention, what we claim as new, and desire to secure by Letters Patent, is—

1. In a weighing apparatus, a fulcrumed scale-beam, hangers and transversely-fixed abutments suspended therefrom and a compartment weighing-bucket pivoted and tilt-able from side to side whereby the discharge-openings are alternately brought into contact with the corresponding abutments, or moved away from them.

2. The combination with a weighing apparatus of a fulcrumed scale-beam, a compartment weighing-bucket pivoted and tiltable upon one end of the beam and adapted to rise and fall therewith, said bucket having discharge-openings at opposite sides, and transversely-fixed abutments carried by the scale-beam and movable up and down in unison therewith and with the bucket, whereby the tilting of the bucket alternately closes the discharge-mouths against the abutments.

3. The combination in a weighing apparatus of a pivoted tilting weighing-bucket having a fixed central partition and a discharge-opening at the outer side of each compartment, a fulcrumed scale-beam upon which the bucket is carried and with which it is movable, a source of supply beneath which the receiving-mouths of the compartments are alternately placed by the tilting of the bucket, and transversely-fixed abutments carried by the scale-beam and movable up and down in unison with the beam and against which the discharge-mouths of the buckets are alternately closed.

4. The combination in a weighing apparatus of a tilting weighing-bucket having a central partition, a fulcrumed scale-beam upon which the bucket is carried, and with which it is movable, a stationary source of supply beneath which the mouth of one compartment is brought while the other is placed in position to discharge after being filled, abutments carried by the scale-beam against which the discharge-mouths are alternately closed by the tilting of the bucket, a latch mechanism by which the bucket is held in position until the compartment is filled and the scale-beam depressed, said mechanism comprising latch-levers fulcrumed at opposite ends to stationary supports, pins by which the depression of the inner end is limited, and stops or catches upon the sides of the bucket with which the

latch-levers alternately engage when the bucket tilts.

5. The combination in a weighing apparatus of a tilting compartment-bucket, a fulcrumed rising and falling scale-beam upon which the bucket is tiltably supported, movable latch-levers having stationary fulcrum-points and latches at the movable ends, stationary stops by which the vertical movement of the latches is limited, other stops carried upon the bucket, one of which engages one of the latches when the bucket is tilted in one direction, and means to disengage the latches from the bucket-stops when the weight of the bucket causes it to sink whereby it is allowed to tilt to the opposite side.

6. The combination in a weighing apparatus of a fulcrumed tilting scale-beam, a compartment weighing-bucket carried by and tilttable upon the end of said beam, a source of supply beneath which the compartments are alternately brought to be filled, latch-levers having their outer ends fulcrumed upon stationary supports, and their inner ends adapted to engage stops upon the bucket whereby it is held in either position to which it may be tilted, said stops being disengaged by the sinking of the scale-beam and bucket when the latter has been filled, and supplemental levers so fulcrumed as to be engaged when the bucket sinks, said levers acting positively upon the latch-levers to disengage them from the bucket-stops.

7. In a weighing-machine, a fulcrumed tilting scale-beam, a compartment weighing-bucket carried upon one end and tilttable to present either compartment alternately to be filled, latch-levers by which the bucket is retained in position until the filling of the compartment is completed, a source of supply, and a hopper intermediate between said source and the weighing-bucket, said hopper having diagonally-disposed direction-boards slidably mounted therein to break the current and change the direction of the passing material.

8. The combination in a weighing-machine of a tilting compartment-bucket, mechanism by which it is locked in either position, a feed-hopper through which material is delivered into the bucket-compartments as they are presented beneath it, direction-boards diagonally disposed with the hopper and by which the current of material passing through the hopper is changed, and means for slidably adjusting said boards to or from each other to vary the direction of the current.

9. The combination in a weighing-machine of a scale-beam, a compartment weighing-bucket tiltably carried upon one end of said beam, a source of supply beneath which the mouth of the buckets are alternately presented, a feed-hopper intermediate between the source of supply and the weighing-bucket, having diagonally-disposed direction-boards, and guides upon which they are slidable to

and from each other whereby the material passing through the hopper is interrupted and its direction of motion changed.

10. The combination in a weighing-machine of a pivoted tilting scale-beam, a tilting compartment-bucket carried upon one end thereof, hangers rigid with the scale-beam and depending therefrom, and abutments carried by the hangers so as to be moved up and down with the scale-beam, to and from which abutments the discharge-mouths of the compartments are alternately moved, a source of supply beneath which the mouths of the bucket-compartments are alternately brought, and 15 a slidably controlling-gate therefor, a horizontally-disposed receiver into which the compartments are emptied, said receiver being fulcrumed at one side, and a rod connecting said receiver with the discharge-gate, where- 20 by a check in the flow of material through

the receiver depresses it and acts to close the gate.

11. The combination in a weighing-machine of a fulcrumed scale-beam, a weighing-bucket pivoted and tiltable thereon, locking and disengaging mechanism whereby the bucket is alternately held with either compartment beneath the source of supply until filled, the said locking device being disengaged by the sinking of the bucket, and a percussive mechanism by which the holding latch or pawl is positively disengaged. 25 30

In witness whereof we have hereunto set our hands.

EDWARD HANAK.
GEORGE HOEPNER.
